PUMP DISCHARGE FITTING

Russell G. Berry, Maplewood, Mo., assignor to
 Carter Carburetor Corporation, St. Louis, Mo.,
 a corporation of Delaware

Application May 15, 1944, Serial No. 535,644

3 Claims. (Cl. 158—36.3)

1

This invention relates to liquid supply systems and consists particularly in a novel replaceable fitting for use in the connection between a fuel pump and carburetor, where the latter is designed to utilize substantially less fuel than that normally supplied by the pump and where the carburetor inlet valve frequently closes entirely, even though the pump continues to operate.

In a co-pending application, Serial No. 473,683, filed January 27, 1943, now Patent No. 2,394,860, in the name of Alfred C. Korte, there is illustrated a centrifugal fuel pump which is operated at a substantially constant speed by an electric motor. In order to use this pump with engines varying widely in capacity and, consequently, fuel requirements, it is necessary to limit the pump output and reduce the maximum pressure produced. Otherwise, the carburetor float valve, when closed, will be subjected to excessive pressures which will cause the float to sink deeper in the constant level chamber and, accordingly, raise the fuel level.

It is an object of the present invention to provide a restriction and by-pass fitting which can be readily inserted in the fuel connection between the pump and carburetor and which will accomplish this purpose.

When such a fitting is used, it is merely necessary to replace this part with a different one in order to adapt the pump for use with an engine and carburetor having substantially different fuel requirements.

In the accompanying drawing which illustrates the invention,

Fig. 1 is a view of an electric fuel pump and carburetor constant level chamber with the novel fitting applied to the connection therebetween, illustrated diagrammatically.

Fig. 2 is an enlarged upper end view of the fitting.

Fig. 3 is a cross section of the fitting.

Fig. 4 is a top view of a modified form of fitting.

Fig. 5 is a section through the fitting in Fig. 4.

The pump in Fig. 1 is operated by electric motor 10 and includes a centrifugal impeller 11 located in voluted casing 12 and at the lower end of motor shaft 13. The entire motor and pump unit is normally submerged in the fuel tank and is connected by tubing 14 to boss 15 forming the fuel inlet of carburetor constant level chamber 16. A valve seat 17 in boss 15 receives needle valve 18 controlled by float 19 so as to maintain a substantially constant level of fuel in bowl 16. Fuel is supplied from bowl 16 to the carburetor in a well known manner through metering jet 20 and upwardly inclined fuel passage 21.

2

A boss 23 forms the fuel outlet connection of the pump. To this boss there is threadedly attached the novel fitting, generally indicated at 24, to which, in turn, is connected tubing 14. The fitting, as best shown in Figs. 2 and 3, includes an internal, apertured web 25 forming a restricted delivery orifice 26, and a fixed orifice 27, located just posterior to restriction 26, which by-passes a portion of the pumped liquid back into the fuel tank.

In operation, it is intended that fitting 24 be used where the normal output of the pump is substantially greater than the normal requirement of the carburetor. Restriction 26 and by-pass 27 are so calibrated and proportioned that the pump output and the load thereon are reduced, accordingly. Furthermore, the restriction and by-pass also cooperate to limit the maximum pressure in tube connection 14 at times when float valve 18 is closed while the pump continues to operate. The restriction and by-pass must be calibrated for each different pump and carburetor installation, but it is only necessary to provide the proper fitting in order to adapt a given pump to a particular engine and carburetor. The fitting is a relatively inexpensive part, while the cost of providing a large number of different pumps might be prohibitive. It is especially adapted for use with a centrifugal type of pump, since the restricted delivery and by-pass orifices have the effect of reducing the delivery and, consequently, the load on the pump at all times. The current required, thus, is reduced and operation made more economical.

In the modification in Figs. 4 and 5, a fixed restriction is provided at 26, as in the preferred form, but by-pass 27a is a threaded plug 31. The functioning of this form is substantially the same as that of the previous form, except that no fuel will be by-passed until sufficient pressure has been built up to unseat check ball 30.

The invention may be modified in various respects as will occur to those skilled in the art, and exclusive use of all modifications as come within the scope of the appended claims is contemplated.

I claim:

1. In combination, a liquid pump, a device having a connection thereto for normally using substantially less of the pumped liquid than the pump is constructed to supply, valve means to intermittently open and close said connection to said device, and a fitting unit in said connection comprising a delivery tube having a restriction and a restricted relief by-pass orifice, said restriction and orifice being calibrated to reduce the

maximum rate of flow of pumped liquid to the maximum required by said device and to limit the maximum pressure in said connection when said valve is closed.

2. In combination, a substantially constant speed, centrifugal pump, a device having a connection with said pump for normally utilizing less liquid than the pump is constructed to supply, a yieldably seating valve for intermittently opening and closing said connection to said device, and a replaceable fitting interposed between said pump and said device comprising a tubular part having a flow limiting restriction and a restricted relief by-pass orifice, said restriction and by-pass being proportioned with relation to each other and to the pump capacity and normal requirements of said device to reduce the maximum fuel supply when said valve is open to the maximum required and to limit the pressure in said connection when said valve is closed to the maximum said valve is constructed to resist.

3. In combination, a constant speed, centrifugal fuel pump, a carburetor having a fuel inlet controlled by a float valve, a connection between said pump and said carburetor, said pump being constructed to supply substantially more fuel than the maximum said carburetor is designed to require, and a replaceable fitting unit in said connection including a fixed fuel delivery restriction and a relief by-pass restriction posterior to said delivery restriction, said restrictions being

calibrated and proportioned to reduce the fuel supply, when said float valve is open, substantially to that required by said carburetor and to limit the maximum pressure in said connection, 5 when said valve is closed, to that which said float valve is designed to resist without altering the constant level of fuel in said carburetor, said bypass restriction also functioning to reduce the pump delivery and consequently the load thereon 10 when said carburetor valve is closed.
